United States Patent

Des. 238,266
Patented Dec. 30, 1975

238,266

MOTORCYCLE SADDLE BAG OR SIMILAR ARTICLE

Byrd E. Dalton, 1227 Crescent Drive,
Glendale, Calif. 91205

Filed July 17, 1972, Ser. No. 272,166

Term of patent 14 years

Int. Cl. D12—11

U.S. Cl. D12—158

FIG.1

FIG.2

FIG.3

FIG.4

FIG.5

FIG. 1 is an isometric view of a motorcycle saddle bag or similar article showing my new design.

FIG. 2 is a front end elevational view.

FIG. 3 is a top plan view.

FIG. 4 is a side elevational view.

FIG. 5 is a rear end elevational view.

The side opposite that shown in FIGS. 1 and 4 is substantially similar to the side shown. The bottom is generally flat and unornamented.

I claim:

The ornamental design for a motorcycle saddle bag or similar article, as shown and described.
